UNITED STATES PATENT OFFICE.

TERON W. FOTHERGILL, OF CHESTER, MASSACHUSETTS, ASSIGNOR TO BURT L. SYMS,
OF BOSTON, MASSACHUSETTS.

INTERNAL-COMBUSTION ENGINE.

1,188,433.

Specification of Letters Patent. Patented June 27, 1916.

Application filed April 11, 1914. Serial No. 831,311.

To all whom it may concern:

Be it known that I, TERON W. FOTHERGILL, a citizen of the United States, residing at Chester, in the county of Hampden and State of Massachusetts, have invented an improvement in Internal-Combustion Engines, of which the following is a specification:

This invention relates to, and is especially advantageous in connection with that class of internal combustion engines of the two-cycle type, in which the pump and cylinder are coaxial, and in which the charge which is compressed prior to ignition in one cylinder is transferred to the ignition chamber of the other cylinder; although, while the features of my invention, hereinafter described, are preferably used in connection with this type of engine, they are not all necessarily so used.

In the normal operation of internal combustion engines of certain types, the burned gases are not thoroughly exhausted from the cylinder before the fresh charge is introduced, sometimes causing the engine to backfire, and sometimes preventing the charge from exploding.

One of the objects of my invention is to provide means whereby the exhaust gases may be quickly discharged from the cylinder and the fresh charge may be supplied by a simultaneous operation in such a manner that the mixing of the two charges will not occur.

Another object of my invention is to provide an improved form of valve mechanism for controlling the supply and discharge to and from the respective cylinders and chambers.

A further object is to provide means whereby the charge will be thoroughly vaporized and mixed with air before it is discharged into a cylinder, so that it will be burned to the best advantage.

I accomplish these objects by the means shown in the accompanying drawing in which:

Figures 1 and 2 are front and rear elevations of an internal combustion engine made according to my invention. Fig. 3 is a centrally longitudinal, sectional view of one of the cylinders and valve chambers, taken at the line 3--3, of Fig. 4. Fig. 4 is a cross-sectional view taken at the line

4--4, of Fig. 3. Fig. 5 is a similar view taken at the line 5--5, of Fig. 3. Fig. 6 is a diagrammatical view showing the relative positions of the parts.

As shown in the drawing the engine comprises a pair of cylinders 1 and 2 which are arranged in parallelism, and of the type above referred to, said cylinder being respectively provided with pistons 4, 4' having working plungers 5, 5', and pump-pistons 6, 6', which respectively operate in the working chambers 8 and 10, and in the pump-chambers 12 and 14 of the cylinders, in the manner usual with this type of engine. Each piston is also connected to the main-shaft 16 by the usual cranks and connecting-rod connections, the cranks being set 180° apart.

The working chambers 8 and 10 are provided with intake ports 18 and 19, and exhaust ports 20 and 21, respectively, and the pump-chambers 12 and 14 with combined inlet and discharge-ports 22 and 23. The cylinders are provided with spark-plugs 24 and 24' at their extreme ends, the ports 18 and 19 being respectively arranged in line therewith.

A valve-operating shaft 25 is arranged in parallelism with the shaft 16 and is driven in the same time thereby through gears 28 and 30, which are respectively mounted upon the shafts 16 and 25, and are of the same size. A pair of piston valves 32 and 32' are mounted in valve-chambers 34, 34' at the side of the cylinders 1 and 2, and have crank and connecting rod connections with the shaft 25, the cranks being arranged 180° apart. Said piston valves are each provided with annular recessed portions 36, 36' adjacent the outer ends thereof, and with similar portions 38, 38' near the inner end, having packings 40, 40' at opposite sides thereof. The inner end of each piston valve is made hollow to provide chambers 42, 42' opening to the ends thereof, and from which ports 43, 43' lead to the side thereof. The inner end of each piston chamber is provided with a projection 44 and 44' which is arranged to extend into the chamber 42, and 42' so as to fill a substantial portion thereof when the valves are in their inner positions, while permitting free movement thereof. The inner end of each projection 44, 44' is provided with a de-

flecting surface 45, 45' which extend obliquely to the inner sides of the ports 18, 19. The inlet pipe 46 from the carburetor leads into the valve chambers 34, 34' through ports 47, 47' which are adapted to be closed by the outer portions of the valves 32, 32'. Said chambers 34, 34' are also provided with pump discharge ports 48, 48' and with intake ports 49, 49', which are controlled by 10 the valves 32, 32'.

The casing 50 is mounted on the outer side of the valve piston chambers, which is provided with a pair of chambers 51 and 51' arranged side by side, the outermost chamber 51' being connected to the ports 48, 49' by short passageways which extend through the chamber 51 at diagonally opposite points, and the inner chamber 51 is directly connected to the ports 48', 49, as indicated 20 in Figs. 4 and 6.

The operation may be best understood on reference to the diagrammatical view of Fig. 6. When the parts are in the relative position illustrated in this figure, the 25 working chamber 8 will have a fresh charge therein held under compression and at the same time the working chamber 10 will have received a fresh charge ready to be compressed. The charge in chamber 8 is then 30 ignited and the piston 4 and valve 32 move outwardly, while the piston 6' and valves 32' move inwardly. The port 47' is immediately closed by the inward movement of the valve 32', so that a partial vacuum is 35 created by piston 6, in the pump-chamber 12, and chamber 51, which is then connected thereto through port 22, recess 36 and port 48, as the piston 4 is moved outwardly. As the valve 32 approaches the outer end of 40 its stroke the annular space 36 thereabout is moved opposite the port 47, so that the gas from the carburetor is quickly drawn by suction, due to the partial vacuum which has been formed, into the chamber 12, and 45 into the communicating chamber 51, the port to the chamber 51 being preferably cut off just before the valve reaches its outer position, as indicated by the positions of the valve 32' and piston 4'. During the out- 50 ward movement of the piston 6', previous to this operation, the chamber 14 will have become filled with a charge of vaporized gas in the manner just described with reference to the chamber 12. As the piston 6' is then 55 moved inwardly the port 49 will be closed and the port 47', which communicates with the carburetor, will immediately be closed, while the port 48' which leads to the chamber 51' will be opened, so that, as the piston 60 6' moves inwardly, the charge in the chamber 14 will be compressed in the chambers 14 and 51'. The discharge port 49 from the chamber 51' will remain closed until the piston 4 has nearly reached the end of its out- 65 ward movement, so that the charge will be

somewhat compressed in the chamber 51'. When the piston 4 moves out far enough to open the exhaust port 20, the port 48, in the valve 32, will be moved into register with the port 49, so that the compressed gas in the chamber 51' will be admitted into the chamber 42 therein, and, as the port 49 is opened, the inner end of the valve 32, which is packed by the packing rings 40, will pass beyond port 18, so that communication will 75 be opened from the chamber 42 to the chamber 8. That is, the valve 32 and piston 4 will be moved to the positions corresponding to the positions of the valve 32', and piston 4', in Fig. 6. On the inward movement of the piston 4 the charge in the chamber 42 will likewise be compressed in the chamber 51, communication with the chamber 10 through the bore 42' of the valve 32 being opened when this valve approaches 80 the outer end of its movement. The charge thus liberated from chamber 51 or 51' will rush through the chamber 32 or 32', as the case may be, against the deflecting surface 45 or 45' and into the chamber 8, or 10. At 85 the same time the exhaust port 20, or 21 will have been opened and the rush of fresh gas into the inner end of the working chamber will sweep the consumed gases before it, and drive them from exhaust port which has 90 been opened by the piston. The parts are so timed, and the relative sizes of the different parts so arranged, that this will be accomplished by the time the working piston moves back to shut off the exhaust port 100 and, as soon as the piston closes the exhaust port, the fresh charges will be compressed, as the simultaneously inward movement of the corresponding valve will close the supply port 18 or 19, and the operation already 105 described will be repeated, the pump of one piston acting to supply the charge to the other piston.

Some of the more important advantages of the operation above described are as follows:—By first forming a partial vacuum in the pump-cylinder and then drawing the charge from the carburetor therein, the completeness of vaporization is greatly enhanced, with a consequent increase in efficiency. The charge is then compressed during the inward movement of the piston and is then expanded as it is discharged into the working cylinder, causing a further mixing or vaporization of the gas, and then, as the gas is again compressed in the cylinder before it is ignited, the hydrocarbon becomes thoroughly vaporized and mixed with air, giving a high efficiency when it is consumed.

By holding the gas under compression, then suddenly discharging it into the extreme inner end of the working cylinder, an effective means for discharging the consumed gases is provided. The rush of fresh gas over the spark-points also materially as- 125

sists in keeping them clean and preventing the accumulation of carbon on the spark points.

It will be noted that the packings 40 of 5 the piston valves are at opposite sides of the intake ports 18 or 19 at the time the explosion takes place, and therefore, the impact of the explosion on the valve is balanced, and at the same time communication 10 is cut off to the carbureter, so that danger of back-firing is avoided.

The projections 44, 44' act to fill the chambers 42, 42' within the valves 32, 32' and the spaces in the ends of the valve chambers 15 34, 34', when the valves are withdrawn therefrom, making practical the employment of the balancing pistons and the supply passages through the body of the valves. The inclined faces of the projections acts as 20 deflectors to direct the charge of compressed gas through the inlet ports.

I claim:

1. An internal combustion engine comprising a working cylinder, a valve chamber having supply and discharge ports at different longitudinal points, said discharge port opening to said cylinder, a valve body in said chamber having a pair of balanced pistons thereon and a longitudinal passage 25 therein opening to said chamber at the opposite sides of said pistons, and means to move said body between positions to open the ends of said passage to said ports and to hold said pistons at opposite sides of said 30 discharge port.

2. An internal combustion engine comprising a working cylinder, a valve chamber closed at one end and having an inlet port and a lateral discharge port opening into said cylinder, a piston valve having a 40 longitudinal bore in the body thereof opening at its inner end to the closed end of said chamber and at its outer end to said inlet port in certain positions thereof, and a projection mounted at the closed end of said 45 chamber and arranged to enter said bore in the inner position of said valve.

3. An internal combustion engine comprising a working cylinder, a valve chamber closed at one end and having an inlet port 50 and a lateral discharge port opening into said cylinder at one side, a piston valve having a longitudinal bore in the body thereof opening at its inner end to the closed end of said chamber and at its outer end to said 55 inlet port in certain positions thereof, and a projection mounted at the closed end of said chamber and arranged to enter said bore in the inner position of said valve, said projection having a deflecting face at its end 60 for directing the flow of gas through said discharge port.

In testimony whereof, I have signed my name to this specification, in the presence of two subscribing witnesses.

HERON W. FOTHERGILL.
